TRAIN DESCRIBING AND RECORDING
SYSTEM

Matthew H. Loughridge, Bogota, N. J.

Application May 24, 1930, Serial No. 455,333

45 Claims. (Cl. 246—107)

This invention relates to a train describing and recording system and has for an object to provide a system which automatically describes and records passing trains at intervals along the trackway. More particularly the invention includes a system in which a mechanism is provided on the train which is adjusted to describe the train as desired and a companion mechanism is provided in dispatchers stations or other locations on the trackway which are connected with ramps or contact rails on the trackway. When the train engages one of the trackway ramps its describing mechanism is initiated and a combination of signals is transmitted to the trackway devices which describe the train and make a permanent record of the train and the time it passed predetermined points on the trackway. Another object of the invention is to automatically describe trains at a plurality of spaced stations on the trackway so that the progress of the train along the track may be determined. Other objects of the invention will be understood from the following specification and the drawings forming part thereof, in which,

Fig. 1 is a front view of the recording mechanism with the cover removed;

Fig. 2 is a side elevation partly sectioned of the mechanism in Fig. 1;

Fig. 3 is a diagram of the controlling circuits for the recording apparatus;

Fig. 4 is a diagrammatic view of the transmitting apparatus on the vehicle or train;

Fig. 5 is a trackway layout showing one arrangement of trackway stations.

In the present invention the transmitting apparatus comprises a stepping mechanism which is adjustable to transmit groups of signals in steps which signals usually designate the train by a number. This apparatus remains inactive but is initiated to make one cycle of operations as soon as a trackway device is encountered. During this cycle the signals produced by the device are transmitted through an electric conductor to one or more receiving stations.

The signals are received through a polarized relay and selectively operate a group of stepping wheels from an initial position according to the number of signals received and upon completion of the signals a tape is brought into contact with the stepping wheels and with the time recording mechanism which registers the signals describing the train and the time that it passed a specific location on the track. By recording the time with the signals and by spacing the recording stations at predetermined intervals on the track-

way it is possible to keep an accurate record of the train over each portion of the track.

In the drawings, 610 is the frame, 611, 612 and 613 are stepping magnets of the recording device; as shown in Fig. 2, when the magnet 613 is energized the armature 614 is raised and through the link 615 and the guide 616 the wheel 623 is stepped around one tooth for each operation of the armature 614. Magnet 611 operates stepping wheel 621 and magnet 612 operates stepping wheel 622 in the manner described according to the principle of a ratchet stepping device. Gear wheel 626 moves with the stepping wheel 623 and engages gear 629 of the wheel 633, carrying the register numerals shown; each step of the magnet 613 moves a different character on 633 into the registering position. The stepping wheel 621, through gears 624 and 627 similarly operates the registering wheel 631 and the stepping wheel 622, through gear 625 and gear 628 similarly moves the registering wheel 632. Thus magnet 611 moves forward the registering wheel 631, magnet 612 moves forward the registering wheel 632 and magnet 613 moves forward the registering wheel 633.

When magnet 617 is energized it attracts the armature 618 and lowers the platen 644 moving on the pivot 645. This platen carries a ribbon of paper between the rollers 647 and 648 so that when the platen is lowered the characters on the registering wheels 631, 632 and 633 are registered on this tape as well as the time on the index 630 which is operated by the clock mechanism shown in Fig. 2 in dotted outline in schematic form. A gear 649 mounted on a ratchet on the shaft of roller 648 engages the fixed rack bar 650 so that as the platen is lowered the gear 649 is rotated and a fresh portion of paper is exposed to the registering wheels. These wheels are suitably inked for registering purposes by means not shown on the drawings. The ratchet on wheel 649 prevents movement of the paper roll on the return of the platen when released by magnet 617.

When the platen is lowered the plunger 643 mounted on shaft 648a of roller 648 is lowered and lowers the plunger 643a through the guide in the base plate to close the circuit controller 695 hereinafter referred to. This also brings the pin 642 below the crank 641 mounted on shaft 640 and normally held horizontal by the weight 641a. When the platen is returned to the raised position by spring 646, plunger 643a is raised and the quadrant 639 on shaft 640 is moved to the right to engage the pad 637a on the lever 637. This

lever is pivoted at 638 and cable 636 connecting to the upper end of this lever is wound on the drum 635 as the stepping wheel 623 is rotated. When the quadrant 639 is deflected by raising the 5 platen 644 it is apparent that the stepping wheel 623 is restored to the normal position. Each of the stepping wheels 621, 622 and 623 is provided with a drum 635 and a restoring mechanism similar to that described.

10 The wheel 626 is provided with an insulated ring 696 which is engaged by the contact fingers 697, 698 and 699. In the normal position shown in Fig. 2, the contact fingers 697 and 698 are connected in circuit while contact finger 699 rests 15 upon insulation. As soon as wheel 623 makes the first step, the contact finger 697 is disconnected from 698 and contact fingers 698 and 699 are electrically connected by the ring 696 throughout the remainder of the movement of wheel 623. 20 The purpose of these circuit controllers is hereinafter described in connection with the operating circuits.

The transmitting mechanism as illustrated in Fig. 4, comprises the stepping magnet 660, provided with an armature 661, suitably connected by a lever to the stepping arm 662 which engages the stepping wheel 663, mounted on the shaft 664. This wheel is provided with an insulated ring 665 which is engaged by the contact fingers 654 30 and 655. In the normal position shown, the finger 654 rests upon insulation, but upon the first step of wheel 663 the contact fingers 654 and 655 are electrically connected throughout the remainder of the movement of the stepping wheel.

35 The battery 652 653 has a central connection to ground at 651 and connects by wire 659 to one side of magnet 660 and from this magnet to contact 654, ring 666 contact 655, wire 656, armature 661 in the deenergized position and wire 658 40 to battery 652. A shunt circuit is provided around the contacts 654 and 655 by wires 656 and 657 when the contacts 674a and 674b are bridged by the trackway conductor 606. Thus the trackway device 606 initiates the operation of the transmitting 45 device by energizing magnet 660 to produce the first step of wheel 663 and thereafter this wheel continuously rotates through the circuit established by contacts 654 and 655 and interrupted by the movement of armature 661 until 50 a complete cycle of operation is made.

A contactor 674 is provided on the vehicle to engage the trackway conductor 605; this contactor is connected to the transmitting mechanism at 672 and to contact finger 671. Mounted 55 on shaft 654 are the code transmitting segments 666, 667 and 668. These segments are insulated from the shaft 64 and are non-rotating. The number of teeth in each of these segments that may be exposed to the spring contact 671 is 60 adjustable by the quadrant 669, arranged to cover one or more of the teeth of 666 and the quadrant 670 arranged to cover one or more of the teeth on 667. It will be noted that segments 666 and 668 connect by wire 658 to the 65 positive side of the battery and segment 667 connects by wire 659 to the negative side of the battery.

The stepping wheel 663 carries the contact member 671 over the exposed teeth in the segments 666, 667 and 668 and thereby establishes a circuit from the positive or negative side of the battery with the contact 672 through 671 and the supporting mechanism. Thus during the operation of the transmitter, positive impulses are 70 transmitted to the line 608 through conductor 605

for each exposed tooth on the quadrant 666 and, as soon as the contact 671 engages the quadrant 669, a continuous positive impulse is transmitted. When contact 671 engages quadrant 667, negative impulses are transmitted to the line in accordance with the number of exposed teeth in this quadrant and when 670 is engaged a continuous negative impulse is transmitted; following this a positive impulse is transmitted from 668. The number of impulses transmitted by 666 and 667 may be used to describe the train according to a number which is adjustable as described and, if desired, additional stepping quadrants may be provided to increase the number of characters in the transmitted code.

The operation of the registering device will be understood from Fig. 3 in which the polarized relay 680 is connected to the line 608 and is grounded at 651 so that the armature 679 of this relay is deflected to the right or to the left in accordance with the polarity of the current from the transmitter. When in the position shown the code signal received on wire 608 is connected through armature 679 by wire 681 with contact finger 688 of stepping wheel 621 for mechanism y 25 and by wire 683, contact fingers on stepping disc 622 of mechanism x to wire 685 and stepping magnet 611 for the stepping wheel 621 of instrument x. This steps around stepping wheel 621 in accordance with the number of impulses received of this 30 polarity and places the index wheel 631 in position to register a character in accordance with the first group of code signals received.

When the polarity of the current in the line wire 608 is reversed, the armature 679 is reversed and a circuit is established through wire 682, contact fingers 693 and 699, wire 688, contact finger 697 and wire 690 to stepping magnet 612 for the stepping wheel of 622 of instrument x. This steps around the index wheel 632 in accordance with the second group of code signals transmitted.

When the current in the line wire 608 is again reversed the armature 679 connects through wire 681, contact ring 696 of stepping wheel 621 for instrument y, wire 683, contact ring 696 of disc 622 for instrument x and wire 691 to stepping wheel 613. Stepping magnets 611, 612 and 613 it will be noted are grounded on wire 651.

This causes the index wheel 633 to be stepped 50 around in accordance with the third set of code signals received.

When the impulses on the line 603 are again reversed a circuit is established through contact 679, wire 682, contact ring 696 of stepping wheel 621, wire 683 contact ring 696 of stepping wheel 622, wire 692 to magnet 617 and to ground on 651. When magnet 617 is energized, 618 is lowered to close the contact at 695 which establishes a circuit from the line wire 603 to magnet 617 thereby holding this magnet energized directly by the current on the line wire 603. This magnet is slow releasing so that once it is energized it will remain in the energized position during any momentary interruptions of the line circuit such as would occur in the steps of the transmitted signals. Thus when magnet 617, which is not polarized, is energized to register the code signal it will not register again for subsequent signals until another trackway station is encountered. 70 Continued steps of the circuit energizing magnet 617 merely results in holding this magnet energized. Once the armature of this magnet has been moved to the energized position, the line circuit is directly connected to this magnet 75

through 695 and independent of the mechanism.

Magnet 617 is slow releasing to the extent of the time interval between steps of the same character, but the time interval between each group of steps is much greater than the interval between the steps themselves. This will be understood by the operation of motor 660 and the positions of the toothed quadrants 666 and 667. In consequence, magnet 617 releases its armature between the groups of steps but not between the steps themselves. Thus, if impulses are received from the line after magnet 617 is energized, without changing the polarized relay 680, magnet 617 will remain energized and no further action takes place. If impulses are received from the line which changes the polarized relay, such as would result from a second operation of the transmitter, or from another transmitter, the interval between the change in the impulses of the new group from the old impulses, permits magnet 617 to deenergize, thereby restoring the apparatus to normal position for a new operation. Magnet 617 controls itself through circuit controller 695 and when the circuit through 695 is deenergized and magnet 617 releases its armature, the apparatus is restored to the starting position through 639 and 637. If magnet 617 is constructed with a time interval greater than the interval between the steps and the interval between the groups of steps, it will simply remain energized by the impulses on the line 608, through contact 695. It should be noted that the transmitter, Fig. 4, makes only one revolution, or cycle of operation each time it is initiated.

The apparatus described shows how code signals of three characters or groups may be received and registered on the instrument *x*. In addition to this the diagram shows how the system may be applied to selectively operate two registering instruments, the other instrument being indicated by *y* and which will now be described.

If the first impulse received on the line 608 reverses the position of the polarized relay 680 from that shown then a circuit will be established from 679 to 682, contact fingers 697 and 698, wire 684, contacts on ring 696 of stepping wheel 622 for instrument *y* and wire 686 to stepping magnet 611 which is grounded on wire 651. This causes the index wheel 631 of instrument *y* to register the first signals of the code. When the polarity of the current on the line wire is reversed a circuit is established through 679, wire 681, ring 696 of stepping wheel 621 for instrument *y* and wire 687 of stepping magnet 612 which is grounded on wire 651. This causes the index wheel 632 to step around in accordance with the second code signal from the transmitter.

If the line impulses are again reversed in polarity a circuit is established from 679 through wire 682, stepping wheel 621, wire 684, stepping wheel 622 of instrument *y* and wire 688 to the registering magnet 617 for instrument *y*. This magnet is slow releasing and when energized closes a circuit at 695 which directly connects the magnet to the line wire 608 and maintains it in the energized position as long as the line wire 608 is energized. This magnet is similar to the corresponding magnet on instrument *x*. It will be noted that by controlling the stepping magnets by the stepping wheels to be subsequently operated, a selective control is obtained for these magnets; also by controlling the stepping magnets of one instrument by the other instrument 70 a selective control is obtained which insures that

only one registering instrument can operate at a time.

The transmitting device in Fig. 4 may be applied to operate the registering device in Fig. 3 as follows: The exposed teeth on quadrant 666 5 are arranged to transmit six impulses which will step around the stepping wheel 621 of instrument *y* thereby bringing the numeral 6 on the index 631, under the platen 644. The polarity of the current is then reversed as the six impulses produced by quadrant 667 are transmitted to the line to operate the stepping wheel 622 and bring the numeral 6 of the index 632 under the platen 644. The next impulse produced by 10 668 energizes magnet 617 and registers the signals thus 15 transmitted as the transmitting mechanism completes its cycle of operation.

This system may be applied to a railroad track as indicated in Fig. 5 in which 601, 602 and 603 are dispatcher stations and 605 are trackway 20 stations for receiving the impulses from the passing vehicle. A line wire 608 connects each of the trackway contacts 605 with a dispatcher station and preferably with two dispatcher stations in multiple as indicated on the drawings. Thus 25 a train entering the track from the left will be simultaneously described in dispatcher stations 601 and 602 and this train will later be described at the next trackway station in the dispatcher stations 602 and 603. If the average running 30 time between the trackway devices is known it is apparent that when a train registers at the first station it should register again within a predetermined time interval at the next station. 35 Where a switch is in the track as at 21 it is apparent that a train which registers in 602 at the first trackway instrument and does not register at the second trackway instrument has been switched at 21 to another track.

Trains operating on track 252, Fig. 5 are supposed to be spaced by a block system of the usual type, not shown in the drawings. By properly arranging the conductors 605 relative to the block spacing of trains, it is possible to prevent two trains being in position to engage conductors 605 connected to the same line wire, at the same time, thereby avoiding confusion in the operation of the system.

This system relates to train describers in general and may be used in regular railroad service, 50 or may be used with an automatic system as disclosed in U. S. Patent 1,381,317, June 14, 1921.

The conductor 608 may be connected to one contactor 605, or a plurality, and this operation may be embodied in the block system as disclosed 55 in U. S. Patent 1,857,760, May 10, 1932, which discloses the general features of the present application.

In the operation of this system, the transmitter, Fig. 4 may be located on the trackway 60 and initiated by the passing train and arranged to operate a remotely located recorder. The invention as described admits of a variety of applications of which the drawings only illustrate one form. It may be applied complete as shown, 65 or applied in part only, or in combination with other systems.

The recording mechanism, as shown in the drawings, is a developed mechanism for making a permanent record automatically of the conditions on the trackway caused by train movements. This mechanism is the translating means by which the received impulses are made intelligent to the operator and the term "recording mechanism" is used herein in a generic sense 70 75

- for such a translating means, except where specifically limited by the structure of the claims. The transmitting mechanism is a typical representation of an impulse transmitter, a variety of which, suitable for practising this invention are commercially available.
- Having thus described my invention, I claim;
1. A train describing system comprising a transmitting mechanism, a recording mechanism on the trackway, for making a permanent record, means partly on the trackway and partly on a passing vehicle for automatically initiating said transmitting mechanism and means for communicating electrical impulses in groups with distinctive characteristics from said transmitting mechanism to said recording mechanism.
  2. A train describing system comprising a transmitting mechanism on the train, a recording mechanism on the trackway, means for automatically initiating said transmitting mechanism, means for communicating signals from said transmitting mechanism to said recording mechanism and means for making a permanent record of said signals.
  3. A train describing mechanism as claimed in claim 2 with means for recording the time the signals are received by the recording mechanism.
  4. A train describing mechanism comprising a transmitting mechanism on the train arranged to transmit signals in groups, a recording mechanism on the trackway, means for communicating said signals from said transmitting mechanism to said recording mechanism and means for selectively operating said recording mechanism by said groups of signals.
  5. A train describing mechanism comprising a transmitting mechanism on the train, a plurality of recording mechanisms on the trackway, means for communicating signals from said transmitting mechanism to said recording mechanisms and means for selectively operating said recording mechanisms.
  6. A train describing mechanism comprising a transmitting mechanism on the train, a plurality of recording mechanisms on the trackway, means for communicating signals from said transmitting mechanism to said recording mechanisms and means whereby only one of said recording mechanism can be operated by said signals at a time.
  7. A train describing system comprising a transmitting mechanism on the train, a recording mechanism on the trackway, means for communicating signals from said transmitting mechanism to said recording mechanism, means for making a record of said signals and means for automatically restoring said recording mechanism after each operation.
  8. A train describing system comprising a transmitting mechanism on the train, a recording mechanism on the trackway, means for communicating signals of a distinctive characteristic from said transmitting mechanism to said recording mechanism and a relay selectively responsive to the characteristic of said signals controlling said recording mechanism.
  9. A train describing system comprising a transmitting mechanism on the train, a recording mechanism on the trackway, means for communicating signals from said transmitting mechanism to said recording mechanism of an intermittent character and a slow acting magnet operated by said signals for operating said recording mechanism.
  10. A train describing system comprising a transmitting mechanism on the train arranged to transmit electrical impulses, a motor for operating said transmitting mechanism, means for automatically operating said transmitting mechanism for a single cycle of operation only at a time, a recording mechanism on the trackway, and means for communicating said impulses to said recording mechanism.
  11. A train communicating system comprising a transmitting mechanism on the train transmitting signals of a particular characteristic, a motor for operating said mechanism, a trackway conductor, a device on the train coacting with said trackway conductor to transmit said signals from the train to the trackway and a plurality of recording devices connected with said conductor, selectively responsive to the characteristic of said signals and means for operating only one of said recording devices at a time.
  12. A train describing system comprising an electric transmitting mechanism on the train, means for automatically operating said mechanism, a plurality of spaced trackway conductors, means for connecting said transmitting mechanism with said conductors as the train passes along the track, and a recording mechanism connected in multiple circuit with said conductors and operated by said transmitting mechanism.
  13. A train describing system comprising a transmitting mechanism on the train, a trackway conductor, means connecting said trackway conductor with said transmitting mechanism as the train passes along the track and a plurality of recording mechanisms connected with said trackway conductor and simultaneously operated by said transmitting mechanism.
  14. A train describing system comprising a transmitting mechanism on the train, a trackway conductor, means connecting said trackway conductor with said transmitting mechanism as the train passes along the track and a plurality of recording mechanisms connected with said trackway conductor and operated by said transmitting mechanism and means for recording the time at which said recording mechanisms operate.
  15. A train describing system comprising a transmitting mechanism on the train, means for automatically operating said mechanism, a plurality of spaced conductors on the trackway operatively connected with said transmitting mechanism as the train passes along the trackway and a recording mechanism connected with said conductors and operated by said transmitting mechanism and means for recording the time at which said recording mechanism operates.
  16. A train describing apparatus comprising a transmitting mechanism on the train for transmitting a series of electrical impulses in succession describing the train, a motor for operating said transmitter, means for closing the circuit of said motor to cause the initiating of said transmitter, means in said transmitter, after it is initiated, for maintaining the circuit of said motor, means on the track-way for receiving the electrical impulses from said transmitter and translating means operatively connected with said receiving means.
  17. A train communicating system comprising a transmitting mechanism on the train having a stepping wheel producing impulses describing the train and initiated by the movement of the train, means for blanking the steps of said wheel to vary the number of said impulses, a receiving device selectively responsive to the number of said impulses from said transmitter and a line

circuit connecting said transmitter and receiver.

18. A train describing system comprising a transmitting mechanism on the train arranged to transmit a series of impulses in groups describing the train, means embodied in said mechanism for varying the impulses in each group, means on the trackway for receiving the impulses from said transmitter and translating means operatively connected with said receiving means.

19. A train describing apparatus comprising a transmitting mechanism on the train transmitting a series of positive impulses, alternately with a series of negative impulses describing the train, means on the trackway receiving said impulses and a translating device operatively connected with said receiving means and selectively responsive to the impulses from said transmitting mechanism.

20. A train communicating system comprising a transmitting mechanism on the train, transmitting in succession a series of electrical impulses describing the train, a device on the trackway receiving said electrical impulses and a translating device having a slow releasing magnet controlling its operation, said device operatively connected with said receiving device.

21. A train communicating system comprising a transmitting mechanism on the train, transmitting a series of electrical impulses in groups describing the train, a receiving device on the trackway, a register device on the track-way having a stepping wheel for each group operatively connected with said receiving device and moved electrically from an initial position by said impulses, indexing characters associated with each of said wheels and means for registering the position of said wheels when the transmitting impulses are completed.

22. A train describing system comprising a transmitting mechanism on the train for transmitting electrical impulses to describe the train, a receiving device on the trackway and a registering device on the track-way connected with said receiving device, having characters positioned electrically by said impulses and a platten for recording said characters when the impulses are completed.

23. A train describing system comprising a transmitting mechanism on the train for transmitting electrical impulses to describe the train, a receiving device on the trackway, a register device on the trackway connected with said receiving device, having characters positioned electrically by said impulses and characters recorded in time and a platen for recording said characters when the impulses are completed.

24. A train describing system comprising a transmitting mechanism on the train transmitting a series of electrical impulses describing the train, a receiving device on the trackway, a register device on the track-way connected with said receiving device, having characters positioned electrically by said impulses, a platten with a paper roll for recording said characters and means for moving said paper roll after each operation of said registering device.

25. A train describing system comprising a transmitting mechanism on the train, transmitting electrical impulses describing the train, a receiving device on the trackway, a register device on the trackway with a paper roll, means for automatically bringing said paper roll and said characters into engagement when said impulses are completed, means for rotating said paper roll in one direction, after each operation

of said registering device and electrical means for operating said registering device by said impulses through said receiving device.

26. A train describing system comprising a transmitting mechanism on the train, transmitting electrical impulses describing the train, a receiving device on the trackway, a register device having designating characters on the trackway with a paper roll, means for automatically bringing said paper roll and said characters into engagement when said impulses are completed, means for restoring said characters to their initial position after they have been registered on said paper roll and electrical means for operating said registering device by said impulses through said receiving device.

27. A train describing system comprising a transmitting mechanism on the train, transmitting electrical impulses describing the train, a receiving device on the trackway, a register device on the trackway having index characters, a frame with a paper roll, means for automatically moving said frame to bring said paper roll and said characters into engagement when said impulses are completed, means controlled by the movement of said frame for restoring said characters to their initial position and electrical means for operating said registering device by said impulses through said receiving device.

28. A train describing apparatus comprising a track with a train, a conductor on the trackway, means on the train for impressing upon said conductor intermittent impulses having particular characteristics describing the train, a recording device connected with said conductor and means for permanently recording said impulses selectively according to said characteristics.

29. A train describing apparatus comprising a track with a train, a conductor on the trackway, means on the train for impressing upon said conductor impulses in groups having particular characteristics describing the train, a translating device connected with said conductor and means embodied in said device operated by said impulses and selectively operated by said groups.

30. A train communicating system comprising a track with a train, a conductor on the trackway, means for impressing upon said conductor impulses in groups, each group having a particular characteristic, by the presence of a train on the track, a translating device connected with said conductor, said device comprising a stepping magnet for each group selectively operated by each group and a slow acting magnet for registering the steps set up by said stepping magnet.

31. A train communicating system comprising a track with a train, a conductor on the trackway, means for impressing upon said conductor impulses in groups, each group having a particular characteristic, by the presence of a train on the track, a translating device connected with said conductor, said device comprising a stepping magnet for each group selectively operated by each group and a slow operating magnet for registering the steps set up by said stepping magnet.

32. A train communicating system comprising a track with a train, a conductor on the trackway, means on the train for impressing upon said conductor impulses in groups, each group having a particular characteristic, a translating device and a polarized relay connected with said

- conductor, said device comprising a stepping magnet for each group and said relay selectively operating said stepping magnets according to said groups.
5. 33. A train communicating system comprising a track with a train, a conductor on the trackway, means at predetermined intervals on the trackway for communicating between said conductor and the train, means on the train for impressing upon said conductor impulses in groups, each group having a particular characteristic and a translating device connected with said conductor, said device comprising a stepping magnet for each group of impulses selectively operated by said groups, index members operated by said stepping magnets, other index members operated by a timing device and means for recording the position of said index members and the time.
10. 34. A train communicating system comprising a transmitting mechanism on the train transmitting signals according to a pre-arranged code and a recording mechanism for recording said signals, means for operating said transmitting mechanism after it is initiated, means for initiating said operating means by the movement of the train on the track, said recording mechanism making a record describing the train and a record of the time and means operatively connecting said recording mechanism with said transmitting mechanism.
15. 35. A train communicating system comprising a transmitting mechanism on the train transmitting impulses of long and short duration describing the train, means for operating said transmitting mechanism after it is initiated, means for initiating said operating means by a passing train, a recording mechanism having index members, means operatively connecting said transmitting mechanism with said recording mechanism for operating said index members by said impulses and means for making a permanent record of the position of said index members.
20. 36. A train describing system comprising a transmitting mechanism on the train transmitting electrical impulses for describing the train, means for operating said transmitting mechanism after it is initiated, means for initiating said operating means by a passing train, a recording mechanism having index members and means indicating time, means operatively connecting said transmitting mechanism with said recording mechanism for operating said index members by said impulses and means for making a permanent record of the position of said index members and the time.
25. 37. A train communicating system comprising a transmitting mechanism on the train for transmitting electrical impulses describing the train, means for adjusting said mechanism to vary the number of impulses transmitted, means for operating said transmitting mechanism after it is initiated, means for initiating said operating mechanism by a passing train, a recording mechanism for recording said impulses and means operatively connecting said transmitting and recording mechanisms.
30. 38. A train communicating system comprising a transmitting mechanism on the train for transmitting electrical impulses in groups according to a prearranged code for describing the train, means for adjusting said mechanism to vary the number of impulses in each group, means for operating said transmitting mechanism after it is initiated, means for initiating said operating mechanism by a passing train and a recording mechanism responsive to said impulses operatively connected with said transmitting mechanism.
35. 39. A train communicating system comprising a transmitting mechanism on the train for transmitting impulses initiated by the movement of the train and describing the train, a recording mechanism having an index member operated by said impulses and a time operated member, a platten with a record sheet arranged to be brought into engagement with said members and means for automatically bringing said sheet into engagement with said members after said index member has been operated.
40. 40. A train communicating system comprising a transmitting mechanism on the train and initiated by the movement of the train for transmitting impulses, a plurality of recording mechanisms at different locations, a single circuit connecting said transmitting mechanism with said recording mechanisms and a relay for selectively operating said recording mechanisms by said impulses.
45. 41. A train communicating system comprising a transmitting mechanism for producing a series of impulses, a receiving mechanism having parts, each responsive to one of said series and means for registering the position of said parts, a single line circuit operatively connecting said transmitter with said receiver and means for preventing the operation of said parts by other impulses after the registering means has operated.
50. 42. A train communicating system comprising a transmitting mechanism for producing a series of impulses, a receiving mechanism having parts each responsive to one of said series and means for registering the position of said parts, a single line circuit operatively connecting said transmitter with said receiver and means for connecting the line circuit directly with said registering means by the operation of said registering means.
55. 43. A train communicating system comprising a transmitting mechanism on the train for producing a series of impulses, means on the trackway at a plurality of locations for receiving said impulses, a translating device on the trackway responsive to said impulses, a single circuit connecting each of said trackway means with said translating device and means for indicating the particular trackway device sending the impulses.
60. 44. A selective system comprising a transmitter, transmitting predetermined impulses, a receiving device electrically connected with the transmitter and having a member moved from an initial position by said impulses, a spring for resetting said member to the initial position and means for bringing said spring into operation to restore said member by one of said impulses.
65. 45. A selective system comprising a transmitter transmitting predetermined impulses, a receiving device electrically connected with the transmitter and having a plurality of members moved from an initial position by said impulses and a recording frame, a spring associated with the recording frame for resetting said members and frame to the initial position and means for bringing said resetting means into effective operation by the last impulse affecting the receiving device.
